UNITED STATES PATENT OFFICE.

NEIL McDONALD, JR., OF COLEMAN, MICHIGAN.

MAIL-BOX.

1,204,580.

Specification of Letters Patent. Patented Nov. 14, 1916.

Application filed March 2, 1916. Serial No. 81,705.

To all whom it may concern:

Be it known that I, NEIL McDONALD, Jr., a citizen of the United States, residing at Coleman, in the county of Midland and 5 State of Michigan, have invented certain new and useful Improvements in Mail-Boxes, of which the following is a specification, reference being had to the accompanying drawings.

10 This invention relates to mail boxes used on rural free delivery routes or in other situations of like character, and the general object of my invention is the provision of a mail box so constructed that rain will not 15 enter the box and damage the mail contained therein, and also so constructed that when the box is unlocked the mail containing section of the box will be projected into such 20 position that the carrier can readily collect 25 the mail therefrom or deposit mail therein.

Still another object of my invention is the provision of an indicator or signal mounted upon the box in such manner that it may be readily shifted to indicate the presence 25 of mail in the box but which will be automatically shifted from its display position when the box is closed.

Other objects will appear in the course of the following description.

30 My invention is illustrated in the accompanying drawings, wherein:

Figure 1 is a vertical section of a mail box constructed in accordance with my invention; Fig. 2 is an end elevation of the 35 box shown in Fig. 1, with the front plate of the drawer partially broken away; Fig. 3 is a side elevation of the construction illustrated in Fig. 1, showing the drawer open and the signal projected; and Fig. 4 is a 40 top plan view of the construction shown in Fig. 3 partly in section, showing in dotted lines the drawer opened.

Referring to these figures, 10 designates 45 the outer section or casing of the mail box, the upper wall or top being rounded so that it will shed water. The bottom 11 of the box is formed with a slot 12 and with a downwardly depending flange 13 at its forward end. Slidably disposed within the 50 casing or section 10 is a drawer 14 which has a sliding fit in the casing and rests upon the bottom thereof, this drawer having a front wall 15 having an area greater than the cross section of the casing 10 so that 55 when the drawer is fully shifted in, the margin of the wall 15 will close against the end

of the casing 10. Attached to the flange 13 is a spring 16 which at its rear end is connected to the bottom of the drawer 14, this spring being of such strength as to project 60 the drawer at least half way out of the casing when the locking devices on the casing are released.

In order to lock the drawer in its closed position, I preferably provide the upper portion of the casing 10 with the forwardly extending resilient strip 17, this strip being formed at its forward end with the upwardly projecting detent 18 having a beveled face 19. This head, when the drawer is 70 closed, is adapted to pass through a slot 20 in the front wall 15 and lock the drawer closed. It may be held in this locked position by any suitable locking means, such as a padlock, if desired. But it will be seen 75 that if the padlock is removed the head 18 may be forced downward and that then the spring 16 will cause the drawer to be projected a certain distance.

The signal which I have devised for the purpose of indicating the presence or absence of mail within the box comprises an arrow-shaped body 21 which is mounted preferably upon the side of the box, this arrow-shaped body having a head 22 at its 80 rear end and a head 23 at its forward end. The shank of this indicator 21 passes beneath a metallic strap or any other suitable guide, the strap being used for illustrative 85 purposes and being designated 24. The head 22 prevents the indicator from being drawn in one direction entirely out of engagement with the strap 24, while the head 23 prevents it from being entirely withdrawn in the other direction. The strip of metal forming this indicator is sufficiently 90 resilient so that it may be drawn laterally outward to pass the projecting margin of the wall 15 of the door so that it may be 95 drawn outward to its full extent to indicate the presence of mail within the box. When the drawer is drawn outward, however, the wall 15 will pass the head 23 and the indicator will spring back into position behind the margin of the wall 15 so that when the 100 drawer is released or forced inward it will shift the indicator rearward to its normal position. It will be seen that by this means the indicator is rendered automatic in its 105 action in that after mail has been removed the indicator will be automatically shifted 110 to a position where it will not be displayed.

Indicators at present in use on mail boxes of this character may be accidentally displayed even after the mail has been removed, and there is no means used for interlocking the 5 indicator with the drawer so as to cause it to be shifted to its non-display position when the drawer is closed.

For the purpose of supporting mail within the mail box, I provide the drawer 14 10 with the upwardly extending mail grasping rack 25 which consists of strips of metal, vertically disposed, and in which letters or like matter may be inserted so that when the postman or carrier opens the box he is 15 not obliged to pick the mail off the bottom of the box but the mail is supported in position where it may be readily grasped. Brackets are attached to the box in any suitable manner whereby it may be connected 20 to a post or other support.

It is of course obvious that many changes may be made in the details of construction of this device without departing in any manner from the invention. It may be 25 modified in many ways to suit different exigencies of operation, but it is particularly adapted for use on rural mail delivery routes, as before stated. By providing the spring 16, I provide for an automatic projection 30 of the drawer so that the carrier is not obliged to pull it out. Furthermore, the

box is so constructed that the mail matter is entirely protected from the weather, there being no joints in the top of the box but only at the end thereof. Thus the mail is 35 not liable to get wet and damaged in heavy storms.

Having described the invention, what I claim is:

The combination with a mail box includ- 40 ing a casing and a drawer slidable therein, the end of the drawer projecting beyond a side wall of the casing, of an indicator slidably mounted upon the side wall of the box and normally disposed inward of the edge 45 of the projecting portion of the wall of the drawer, the indicator being resilient so that it may be deflected beyond said wall and pulled outward, and stops limiting the movement of the indicator to an extent permitting the drawer to be drawn out with its front wall in advance of the forward end of the indicator whereby the indicator will spring inward behind said front wall and will be shifted rearward with the drawer. 50

In testimony whereof I hereunto affix my signature in the presence of two witnesses.

NEIL McDONALD, JR.
